Alexander B. Musichuk, Talmadge, Ohio, assignor to
M. T. & D. Company, Cleveland, Ohio, a corporation of Ohio

Filed Mar. 17, 1961, Ser. No. 64,358

Term of patent 14 years

(Cl. D34—15)

FIG. 1 is a perspective view from the rear quarter of a velocipede frame cover showing my new design;

FIG. 2 is a perspective view from the side of the new design;

FIG. 3 is a top view; and

FIG. 4 is a side view.

The broken line showing of a velocipede in FIGS. 1 and 2 is for illustrative purposes only.

I claim:

The ornamental design for a velocipede frame cover, substantially as shown and described.
